L. S. ABBOTT

FURNACE ARCH HOLDER

Filed Dec. 21, 1925

Inventor

Lyle Stockton Abbott
By *May S. Gabril*
Attorney

UNITED STATES PATENT OFFICE.

LYLE STOCKTON ABBOTT, OF CHICAGO, ILLINOIS, ASSIGNOR TO CHICAGO FIRE BRICK COMPANY, OF CHICAGO, ILLINOIS, A CORPORATION OF ILLINOIS.

FURNACE-ARCH HOLDER.

Application filed December 21, 1925. Serial No. 76,776.

My invention relates to furnace arch holders and more particularly to a furnace arch holder that yieldingly holds the refractory blocks or bricks in position.

5 It is customary to make the roofs of certain furnaces, such as malleable iron furnaces, air melting furnaces and the like in segmental form so as to permit a portion of the roof to be readily moved for charging 10 the furnace. Because of the high temperatures prevailing in a furnace of this character, the said roofs must be constructed of a refractory material. What is known in the art as bung brick is ordinarily used for 15 this purpose. These bricks or blocks are proportioned so as to form an arch and are held together in arched form by means of clamps or holders of metal, each holder or support being used for holding one row 20 of such bricks or blocks in position. The roof is composed of a series of such rows supported in the manner referred to above, the rows extending transversely across the furnace.

25 Due to the fact that the refractory blocks or bricks are comparatively thin, there is considerable radiation of heat from the bricks, which are mounted under the support, toward said support, causing said 30 support or clamp to become heated and to expand during such heating to a considerable extent beyond the ordinary length thereof, when the parts are cool. As a result, when the bricks are fitted into the 35 support or holder tight enough to prevent the same from falling out when cold, the bricks or blocks will be placed under a considerable pressure when the same are heated as these heat up more rapidly than the metallic parts which are at a greater distance from the area in which combustion is taking place, which pressure causes the life 40 of the brick to be shortened and often causes distortion of the brick.

45 It is a purpose of my invention to provide the holder or supporting member for the bricks or blocks with means engaging the bricks or blocks so as to clamp the same in position and at the same time permit the 50 same to expand due to yielding of said clamping means as the parts become heated. The yielding means is such that the same

will adjust itself as conditions in the furnace change and as the various parts of the device become heated so that the bricks or 55 blocks will always be clamped firmly in position without any undue pressure being exerted between the bricks or blocks.

The means preferably comprises a pair of members engaging the end bricks or 60 blocks of the row and carried by means longitudinally movable along the supporting member together with means for yieldingly moving said brick or block engaging members toward each other to yieldingly hold 65 the blocks or bricks in engagement with each other and with the supporting member.

It is a further purpose of the invention to provide resilient means, preferably compression springs, for accomplishing such 70 yielding engagement of the block or brick engaging members with said bricks or blocks and to provide means for adjusting the compression of the springs to suit various conditions.

75 It is a specific purpose of the invention to provide pivotally supported shoes engaging the end bricks or blocks which are carried by slidible members mounted on the supporting members, said slidible members 80 being urged toward each other by the resilient means and the pivotally mounted shoes being so mounted as to engage the bricks or blocks flatly under all conditions. As the expansion of the bricks or blocks is 85 not the same throughout their thickness from the exposed side thereof to the side thereof adjacent the supporting member, the angular position of the face of the brick in engagement with the shoe varies during the 90 time that the parts are in place and the furnace is in operation. The pivoting in such a manner that the shoes flatly engage is accordingly of great importance, as it provides for a more uniform pressure between 95 the various bricks or blocks and between the end bricks or blocks and the shoes, thus also more uniformly distributing pressure throughout the individual bricks or blocks, which of course, increases the life thereof. 100

Other objects and advantages of my invention will appear as the description of the accompanying drawings proceeds. However, I desire to have it distinctly understood

that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a side elevation of one of my improved arch holding members with the bricks or blocks in place thereon;

Fig. 2 is a section taken on the line 2—2 of Fig. 1 on an enlarged scale; and

Fig. 3 is a section taken on the line 3—3 of Fig. 1 on an enlarged scale.

Referring in detail to the drawings, my improved holder comprises a supporting member 10 that is made in the form of a T-shaped casting having an upstanding web portion 11 and laterally extending flanges 12. The underside of the member 10 is curved in one direction so as to form an arch-like or slightly concave lower face 13, said lower face being straight across transversely, as will be obvious from Fig. 2. The entire member 10 is curved along somewhat similar lines as would be evident from Fig. 1.

Mounted on the opposite ends of the member 10 are the brackets 14, the same being secured in position by means of the bolts 15 or any other securing members extending through the flanges 12 of the member 10. The bracket members 14 are provided with bores 16 therein within which are slidably mounted the blocks or followers 17. The position of the blocks or followers 17 is adjustable by means of the set screws 18 extending through the ends of the brackets 14 and screwthreadedly engaging therewith. A projection 19 is provided on each of the blocks 17 around which engages one end of the coil spring 20, the other end of which extends around a projection 21 provided on the block 22, there being two of said blocks 22 provided on the member 10. The blocks 22, as will be evident from Fig. 2, are provided with flanges 23 embracing the flanges 12 whereby said members 22 are slidably mounted on the member 10. The downward extensions 24 on the members 22 are provided with grooved socket portions 25 into which the partly cylindrical projections 26 on the shoes 27 extend. The shoes 27 are thus pivotally mounted on the members 22, which members 22 are in turn slidably mounted on the flanges of the member 10.

Mounted in engagement with the smooth under face 13 of the member 10 are the refractory blocks or bricks 28 which collectively form an arch, as will be clear from Fig. 1. The bricks 28 are arranged in a row along the member 10 as will be evident from the drawings and the shoes 27 engage the faces 29 of the bricks 28 at the ends of the

row, said engagement being always substantially flatwise due to the fact that the pivot of the member 27 is substantially midway between the lower exposed faces 30 thereof and the faces 31 in engagement with the member 10.

In assembling the device, the members 22 are first mounted in position, after which the brackets 14 are secured in place, then in order to assemble the refractory blocks with the member 10, the screws 18 are turned out to their full extent permitting the members 22 together with the pivotally mounted shoes 27 to be spread apart so that the refractory blocks or bricks 28 can readily be placed in position with their edges 31 in engagement with the lower face 13 of the member 10. The screws 18 are then moved inwardly, forcing the blocks or followers 17 against the springs 21 until they are compressed to such an extent that the slideable members 22 will be moved to such a position that the shoes 27 will clamp the row of bricks 28 between the same. The springs 21 are only compressed to such an extent by adjustment of the members 18 as to slightly more than counteract the end thrust of the blocks 28 forming the arch when cold and when in the position they assume when in the furnace. The lock nuts 32 provided on the members 18 are then tightened to hold said members 18 in adjusted position.

A plurality of the holders with their refractory blocks clamped in position thereon are then assembled in adjoining relation on the furnace. The heating of the furnace causes the expansion not only of the bricks or blocks 28, but of the supporting member 10 as well. Due to the difference in characteristics of the material of the bricks or blocks 28 and of the member 10, however, and due to the radiation of heat from the supporting member 10, there is a considerable difference in temperature between the inner faces 30 of the bricks or blocks 28 and the outer faces 31 of said bricks or blocks. Furthermore, due to the difference in the coefficient of expansion between iron and refractory materials, there is a variation in expansion between the refractory material and the iron supporting member, which variation furthermore varies depending on the rising or falling of the temperature in the furnace. All these factors operating together causes at times a flattening of the arch and consequently, a change in the angle of the faces 29 of the end ones of the bricks 28. This, however, is compensated for due to the pivotal mounting of the shoes 27 on the members 22. Due to the location of the pivotal axis of the shoes 27, the pressure of the shoes is equally distributed on the end bricks at all times. Furthermore, when the expansion of the refractory arch is greater than that of the supporting member 10, the

slidable members 22 are forced further apart, thus compressing the springs 21 to a greater extent.

It will thus be seen that all adjustments necessary to prevent undue pressure on the refractory members 28 and to prevent the same from dropping out of position are made automatically due to the construction of the holder and are not dependent on the attention of a furnace attendant.

While the member 10 is described as being a casting, it can obviously be made in any other manner and the particular shape can be varied as desired, the important feature being that the members 22 are longitudinally movable therealong. The members 22 are so made that the undercut grooves provided between the body portion thereof and the flanges 23 are large enough to allow for a certain amount of play between the flanges 12 and the member 22 and furthermore the extent of the flanges 23 is such to allow considerable play between the web 11 and the ends of the flanges, this being desirable because of the changes in the size of the parts due to heating of the same when in position on the furnace.

It will also be obvious that while the pivoted member or shoe 27 is desirable to obtain the highest efficiency from the device and to obtain a construction that causes the least possible damage to the bricks or blocks 28, these could be dispensed with if desired, and the slidable members 22 could have their substantially flat forward faces 33 directly engaging with the blocks 28.

Having thus described my invention, what I desire to claim and secure by United States Letters Patent is:

1. In a device of the character described, a supporting member, a plurality of refractory blocks lying side by side and engaging said supporting member and means for yieldingly holding said blocks in engagement with each other comprising a pair of members slidably engaging said supporting member and means for yieldingly urging said slidable members toward said blocks.

2. In a device of the character described, an arched supporting member, a plurality of refractory blocks lying side by side and engaging the under side of said supporting member and means for yieldingly holding said blocks in engagement with each other in arched form comprising a pair of members slidably engaging said supporting member and means for yieldingly urging said slidable members toward said blocks.

3. In a device of the character described, an arched supporting member, a plurality of refractory blocks lying side by side and engaging the under side of said supporting member and means for yieldingly holding said blocks in engagement with each other in arched form comprising a pair of mem-

bers slidably engaging said supporting member and means for yieldingly urging said slidable members toward each other to hold said blocks in engagement with each other and with said supporting member.

4. In a device of the character described, a supporting member having laterally extending flanges, a plurality of refractory blocks lying side by side and engaging said supporting member and means for yieldingly holding said blocks in engagement with each other comprising a pair of members embracing the flanges on said supporting member and means for yieldingly urging said last mentioned members toward each other.

5. In a device of the character described, an arched supporting member having laterally extending flanges, a plurality of refractory blocks lying side by side and engaging the flanges on said supporting member and means for yieldingly holding said blocks in engagement with each other in arched form comprising a pair of members embracing the flanges on said supporting member and means for yieldingly urging said last mentioned members toward each other.

6. In a device of the character described, a supporting member, a plurality of refractory blocks lying side by side and engaging said supporting member and means for yieldingly holding said blocks in engagement with each other comprising a pair of members slidably engaging said supporting member and resilient means for yieldingly urging said slidable members toward said blocks.

7. In a device of the character described, a supporting member, a plurality of refractory blocks lying side by side and engaging said supporting member and means for yieldingly holding said blocks in engagement with each other comprising a pair of members slidably engaging said supporting member and compression springs for yieldingly urging said slidable members toward said blocks.

8. In a device of the character described, a supporting member, a plurality of refractory blocks arranged in a row along said member and means for holding said blocks yieldingly in engagement with each other in arch formation comprising members engaging the end blocks of said row, means for yieldingly urging said members toward each other and means embodying a sliding connection and a pivotal connection for mounting said last mentioned members on said supporting member.

9. In a device of the character described, a supporting member, a plurality of refractory blocks arranged in a row along said member and means for holding said blocks yieldingly in engagement with each other in

arch formation comprising members engaging the end blocks of said row, resilient means for yieldingly urging said members toward each other and means embodying a sliding connection and a pivotal connection for mounting said last mentioned members on said supporting member.

10. In a device of the character described, a flanged supporting member, a plurality of refractory blocks arranged in a row along said member and means for holding said blocks yieldingly in engagement with each other in arch formation comprising members engaging the end blocks of said row, 15 resilient means for yieldingly urging said members toward each other and means embodying a sliding connection and a pivotal connection for mounting said last mentioned members on said supporting member.

20 11. In a device of the character described, a supporting member, a plurality of blocks arranged in a row along said supporting member and means for supporting said row of blocks in arch formation from said sup-

25 of blocks in arch formation from said supporting member comprising means on said supporting member engaging the blocks at opposite ends of said row, the means at least at one end of said row comprising a member bodily movable longitudinally of said 30 supporting member, resilient means for yieldingly urging the same toward said row of blocks and tiltable means on said longitudinally movable member engaging the end block of said row adjacent thereto.

35. 12. In a device of the character described, a supporting member, a plurality of blocks arranged in a row along said supporting member and means for supporting said row

40 of blocks in arch formation from said supporting member comprising means on said supporting member engaging the blocks at opposite ends of said row, the means at least at one end of said row comprising a member 45 slideable on said supporting member and resilient means for yieldingly urging the same toward said row of blocks.

same toward said row of blocks.

13. In a device of the character described, a supporting member, a plurality of blocks arranged in a row along said supporting member and means for supporting said row

of blocks in arch formation from said supporting member comprising means on said supporting member engaging the blocks at opposite ends of said row, the means at least at one end of said row comprising a member 55 slidable on said supporting member, resilient means for yieldingly urging the same toward said row of blocks, and a shoe engaging the end block of said row adjacent thereto pivotally mounted on said slidabile 60 member.

14. In a device of the character described, a supporting member, a plurality of blocks arranged in a row along said supporting member and means for supporting said row

of blocks in arch formation from said supporting member comprising means on said supporting member engaging the blocks at opposite ends of said row, the means at least at one end of said row comprising a member slidable on said supporting member, resilient means for yieldingly urging the same toward said row of blocks, and a shoe engaging the end block of said row adjacent thereto pivotally mounted on said slideable member so as to engage flatly with said block at all times. 75 75

15. In a device of the character described, a supporting member, a plurality of blocks arranged in a row along said supporting member and means for supporting said row of blocks in arch formation from said supporting member comprising a pair of members mounted for longitudinal movement on said supporting member, means on each of said last mentioned members engaging the end blocks of said row and means for yieldingly holding said last mentioned means in engagement with said end blocks.

16. In a device of the character described, 90
a supporting member, a plurality of blocks
arranged in a row along said supporting
member and means for supporting said row
of blocks in arch formation from said sup- 95
porting member comprising a pair of mem-
bers mounted for longitudinal movement on
said supporting member, means on each of
said last mentioned members engaging the
end blocks of said row, said block-engaging
means being mounted to engage said blocks
flatly at all times and means for yieldingly
holding said block-engaging means in en- 100
gagement with said end blocks.

17. In a device of the character described, a supporting member, a plurality of blocks arranged in a row along said supporting member and means for supporting said row of blocks in arch formation from said supporting member comprising a pair of members mounted for longitudinal movement on said supporting member, means pivotally mounted on each of said last mentioned members engaging the end blocks of said row and means for yieldingly holding said block-engaging means in engagement with said end blocks. 105 110 115

18. In a device of the character described, a supporting member, a plurality of blocks arranged in a row along said supporting member and means for supporting said row of blocks in arch formation from said supporting member comprising a pair of members mounted for longitudinal movement on said supporting member, means on each of said last mentioned members engaging the end blocks of said row and resilient means for yieldingly holding said block-engaging means in engagement with said end blocks. 120 125

19. In a device of the character described, a supporting member, a plurality of blocks 130

- arranged in a row along said supporting member and means for supporting said row of blocks in arch formation from said supporting member comprising a pair of members mounted for longitudinal movement on said supporting member, shoes pivotally mounted on each of said last mentioned members engaging the end blocks of said row and means for yieldingly holding said 10 shoes in engagement with said end blocks.
20. In a device of the character described, a supporting member, a plurality of blocks arranged in a row along said supporting member and means for supporting said row 15 of blocks in arch formation from said supporting member comprising a pair of members mounted for longitudinal movement on said supporting member, shoes pivotally mounted on each of said last mentioned 20 members engaging the end blocks of said row and compression springs for yieldingly holding said shoes in engagement with said end blocks.
21. In a device of the character described, 25 a supporting member, a plurality of refractory blocks lying side by side and engaging said supporting member and means for yieldingly holding said blocks in engagement with each other comprising a pair 30 of members slidably engaging said supporting member, means for yieldingly urging
- said slidable members toward said blocks and means for adjusting said last mentioned means.
22. In a device of the character described, 35 a supporting member, a plurality of refractory blocks arranged in a row along said member and means for holding said blocks yieldingly in engagement with each other in arch formation comprising members engaging 40 the end blocks of said row, adjustable means for yieldingly urging said members toward each other and means embodying a sliding connection and a pivotal connection 45 for mounting said last mentioned members on said supporting member.
23. In a device of the character described, a supporting member, a plurality of blocks arranged in a row along said supporting member and means for supporting said row 50 of blocks in arch formation from said supporting member comprising a pair of members mounted for longitudinal movement on said supporting member, means on each of said last mentioned members engaging the 55 end blocks of said row and adjustable means for yieldingly holding said block-engaging means in engagement with said end blocks.

In witness whereof, I hereunto subscribe my name this 7th day of December A. D., 60 1925.

LYLE STOCKTON ABBOTT.
